US00D467349S

(12) **United States Design Patent** (10) Patent No.: **US D467,349 S**
 Niedbala et al. (45) Date of Patent: **** Dec. 17, 2002**

(54) **ANALYZER**

(75) Inventors: **R. Sam Niedbala**, Allentown, PA (US);
Michael J. Gausling, Bethlehem, PA (US); **Philip Michael Formica**, Center Valley, PA (US); **John W. Scott**, Perkasie, PA (US)

(73) Assignee: **Orasure Technologies, Inc.**, Bethlehem, PA (US)

(**) Term: **14 Years**

(21) Appl. No.: **29/148,789**

(22) Filed: **Sep. 28, 2001**

(51) LOC (7) Cl. **24-01**

(52) U.S. Cl. **D24/232**; D24/231

(57) **CLAIM**

The ornamental design for an analyzer, as shown and described.

DESCRIPTION

FIG. 1 is a perspective view of an analyzer showing our new design;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a right side elevation view thereof, the opposite side elevational view being a mirror image thereof.

The broken line showing in FIGS. 1, and 2 are for illustrative purposes only and forms no part of the claimed design.
